UNITED STATES PATENT OFFICE.

JEREMY W. BLISS, OF HARTFORD, CONNECTICUT.

STRIKING APPARATUS FOR GONGS.

Specification of Letters Patent No. 26,411, dated December 13, 1859.

To all whom it may concern:

Be it known that I, JEREMY W. BLISS, of the city and county of Hartford and State of Connecticut, have invented certain new and useful Improvements in the Striking Mechanism of Alarm-Bells or "Signal-Gongs," as they are now usually termed, and also in the Arrangement of Such Mechanism, and that the following specification, 10 taken in connection with the drawings, is a full, clear, and exact description thereof.

In the drawings Figure 1 is an elevation of the bell pull. Fig. 2 is a plan of the striking mechanism and bell standard, the 15 bell being removed, and Fig. 3 is a section through the center of the bell pull, bell and striking apparatus.

The nature of the first part of my invention consists in arranging the whole striking 20 mechanism of the bell within the bell itself when the line in which the actuating force moves is at right angles or nearly so to the plane which touches the edge of the bell, or in other words, the first part of my invention 25 consists in arranging the whole of the striking mechanism under cover (or protection) of the hollow of the bell substantially as shown in the drawings when the line in which the actuating wire or spindle travels 30 is parallel to the axis of the bell or nearly so, and the nature of the second part of my invention consists in a peculiar combination of mechanism substantially such as is hereafter described for actuating a bell hammer.

35 My improvements have been devised with special reference to house bells, in which it is important that the mechanism should be concealed for the sake of finish and neatness and when it is desirable that it should be 40 protected from ignorant domestics who might interfere with and disarrange unprotected striking mechanism, and it is obvious that, other things being equal, the cheapest way of protecting and concealing the mechanism is by means of the bell itself. My 45 improvement may however be applied in other localities.

In the drawings I have shown the bell as applied to one side of a door or wall and the 50 pull or knob as projecting from the other side, but desire it to be understood that the knob may be at any distance or in any convenient spot so long as the connecting wire or rod last in the series that comes from the 55 knob and nearest to the bell leads to the

striking mechanism in a line parallel to the axis of the bell or nearly so.

In the drawings a wall or door is shown at *a*, a knob or bell pull at *b*, a gong or alarm bell at *c* supported upon a standard *d*, and the wire or spindle leading from the knob to the striking mechanism is represented at *e*. The wire or spindle is surrounded by a spiral spring one end of which bears upon the inside of the scutcheon and 60 the other against a pin in the spindle and serves to retract the knob after it has been pulled out and let go. For the sake of convenience a face plate such as *f* is attached to the wall or door directly under (or back) of 65 the bell and upon this the whole striking mechanism is mounted. This mechanism consists of a rock shaft arm *g* pivoted at *h*, to which the spindle is connected by a proper link such as *i*. A pin *j* in this arm abuts 70 against another pin *k* projecting from the surface of a slide *l* which is free to move to and fro across the face plate in a right line, being held in place by any suitable guides. A tail or projection *m* is attached to the slide 75 plate and to the outer end of it is attached one end of a spring *n*, the other end of which is attached to a stud secured to the face plate. This spring when free to act causes 80 the slide to move in a direction opposite to 85 that indicated by arrow *z*. Upon the slide is pivoted a swinging catch *o* which is forced by a spring *p* to bear against a stud *g* also attached to the slide.

The hammer *r* is mounted on a wire *s* 90 which moves on a center at *t*, and the hammer is forced toward the bell by a spring *u* taking hold of a wire attached to the hammer wire and having its other end secured to the face plates. When the parts are all 95 in the position shown in Fig. 2 the tail of the hammer wire rests behind the projecting parts of the swing catch *o*. When the knob is pulled the rock shaft descends toward the face plate, the pin upon it causes the stud 100 to move in the direction of the arrow *z* and the swing catch acting on the tail of the hammer wire moves the hammer away from the bell until the catch passes beyond the end of the tail, releasing it, owing to the fact 105 that the tail moves in an arc of a circle and the catch in a right line. When the tail is released the spring *u* forces the hammer to strike the bell, and when the bell pull is released the spring *n* connected to the slide 110

carries it back to its position as shown in Fig. 2. The swing catch owing to its shape and pivoting dodges by the hammer tail and being forced by the spring *p* to resume its former relative to the slide. The rock shaft arm is returned to its place by the spring *n* acting through the slide and pin *k* upon the pin *j* and the spindle assumes its old position owing to the force exerted upon it by the spring which surrounds it.

Now it will be perceived that all of the mechanism is inclosed (or protected) and covered by the bell itself and also protected by it, that unless the eye is placed close to the surface on which the bell is mounted none of it is visible and also that by removing the bell the whole apparatus is in plain sight and accessible for the purpose of cleaning or repair.

20 The mechanism described is sufficiently simple, but other mechanism may be substituted for it and still be within the principles of the first part of my invention, provided such mechanism is substantially inclosed by 25 and concealed under the cavity of the bell

and is so constructed that it may be actuated by a wire or spindle whose line of motion is parallel to the axis of the bell or nearly so.

I claim as of my invention—

1. Arranging the striking mechanism of 30 a bell substantially within the hollow of the bell as specified when the wire which actuates that mechanism moves in lines parallel to the axis of the bell or nearly so—as described.

2. I claim a rock shaft arm arranged and moving with reference to the bell substantially as described in combination with a slide, a swing catch and a hammer and hammer wire and proper springs the whole constituting a striking apparatus substantially 40 such as herein set forth.

In testimony whereof I have hereunto subscribed my name in the city of Hartford on this 12 day of November, 1859.

JEREMY W. BLISS.

In presence of—

A. SHELDON,
GOODWIN COLLIER.
